UNITED STATES PATENT OFFICE.

WILLARD S. ISHAM, OF WASHINGTON, DISTRICT OF COLUMBIA.

PROJECTILE.

1,188,178.

Specification of Letters Patent. Patented June 20, 1916.

Application filed November 18, 1914. Serial No. 872,816.

To all whom it may concern:

Be it known that I, WILLARD S. ISHAM, a citizen of the United States, residing at Washington, District of Columbia, have invented certain new and useful Improvements in Projectiles, as fully set forth in the following specification.

This invention relates to projectiles; and more particularly to the type of projectiles known as torpedo shells, though the invention is not limited to use in shells of this type.

The principal objects of the invention are to provide a shell that will contain a charge chamber of maximum capacity consistent with its outer dimensions and with the stresses to which it will be subjected when fired from a high-powered gun; that will permit the safe use as a bursting charge of various explosives heretofore used only in shorter-chambered shells; that will possess good ballistic equilibrium in flight, notwithstanding its large capacity and length; that will strike and stay in water where other shells will ricochet; and that will permit the use of a nose fuse designed to be set in operation by a blow, said fuse being protected, however, from damage by the ordinary blows to which it might be subjected in handling.

Other objects of the invention will appear as the description proceeds.

According to the present invention, the charge chamber is restricted or reduced in diameter at the base of the shell sufficiently to permit sufficient thickness of material in the walls to withstand the stresses resulting when the shell is fired; and since these stresses diminish toward the point of the shell, the thickness of the walls may be correspondingly decreased toward the point, the capacity of the shell being correspondingly increased. In shells heretofore made having a single charge chamber, such increase in the diameter of the chamber has been accomplished by gradually curving the chamber walls outwardly from the base toward the point of the shell, the interior surface of the chamber thereby forming a conoid with its greater diameter toward the point of the shell. Such interior surfaces when used in short shells are satisfactory; but when they are employed in long shell chambers, where the setback pressure alone may

amount to 10,000 pounds per square inch or 55 more at the base of the chamber, it is evident that the explosive contained in the chamber is much more highly compressed by the additional wedging action of such surface. The resulting pressure in such a 60 shell easily reaches the critical pressure point of the explosive and an explosion results either directly because of the excessive pressure, or indirectly because of the heat resulting from the compression of inclosed air 65 or of gases that may have been liberated from the explosive by more or less rapid deterioration of the explosive after standing some time. To overcome this menace in long- and large-chambered shells I make the 70 inner surfaces of the side walls cylindrical and increase the diameter toward the point by distinct steps or offsets as opposed to a gradual curve, to give the desired increase in capacity. By this method of construc- 75 tion the wedging effect is eliminated and the maximum pressure in the shell charge when fired from the gun cannot exceed that directly due to setback. Furthermore, the in- 80 crease in area at each offset acts as an additional surface to receive and distribute the setback pressure, thereby reducing the pressure at the base of the chamber. In my preferred form these offset or shoulder surfaces are augmented by annular rings or 85 shelves extending into the chamber. These not only increase the area receiving the set- 90 back pressure of the explosive, but prevent slipping or sliding of the explosive along the walls of the shell toward its base, thereby preventing frictional heat or other abrasive effects which might result in causing ex- 95 plosion of the shell charge. The shell may also be provided interiorly with longitudi- 100 nal side fins to prevent the explosive charge from revolving within the shell because of the rotation imparted by the rifling in the gun.

The point or nose of the improved shell is made cup-shaped; and the location of this cupped nose with respect to the remainder of the shell is a matter of importance, as will subsequently appear. As the shell leaves the gun the cup receives the air equally on all its edges and discharges it forwardly 105 from the center of the cup, thereby creating an artificial air point or cone which reduces the shell's resistance in flight. It has been

found in practice that the present shell actually has a longer range of flight than a shell having the usual pointed nose but otherwise exactly similar in form and dimensions.

When a shell has attained to a long range, its axis tends to incline upwardly in front and at an angle to its trajectory. In other words, the shell tends always to remain parallel to its position at the instant of leaving the gun instead of following the downward slope of its trajectory during the latter part of its flight. At long range therefore an ordinary shell is apt to strike its target with glancing instead of direct impact. With the present improved shell, however, when the shell axis tends to incline undesirably the air deflected forwardly and upwardly by the cupped nose produces a downward resultant reaction on the shell point which acts to correct the tendency to undue inclination. The corrective effect of the cupped nose is even more marked when the shell strikes water. The lower edge of the cup catches the water which is deflected forwardly and upwardly, producing a strong downward thrust which depresses the shell point and causes the shell to dive instead of ricocheting. If the shell is provided with a suitable delay fuse arranged to be set in action by retardation of the shell in flight, such, for example, as that disclosed in my copending application Serial No. 838,119, filed May 12, 1914 (Patent No. 1,179,105), the shell thus becomes a mine adapted to explode at a calculable depth below the water and a definite time after striking the same.

In a shell as ordinarily constructed, the cylindrical body portion tapers gently in an ogival curve to a point at the forward end, the rather long sharp nose thus formed diminishing the resistance of the shell and steadyng it in flight and thus increasing its range. This part of the shell is often termed simply the ogival. According to the present invention the ogival, instead of being carried to an actual point, terminates in a cup some distance short of what may be called the virtual ogival point, or the point to which the ogival extends in the ordinary shell. The position of this cup with reference to the virtual ogival point on the one hand, and the ogival base, that is, the locality where the cylindrical body of the shell begins to taper, on the other hand, is a matter of great importance. If the cup is located too near the ogival base the shell is useless since its range of flight is greatly decreased. Furthermore such a shell tends to tumble end over end upon striking water, which the present invention successfully avoids. If the cup or cup-shaped nose be too near the virtual point of the ogival, then the desirable results attained in my improved projectile are not realized because when the shell

strikes water there is not developed a downward resultant thrust of sufficient magnitude to cause the shell to dive and keep it from ricocheting.

Although the location of the cupped nose on the ogival may be varied within reasonable limits, I have found that the best location is approximately at a locality where the diameter of the ogival is about one-half the diameter of the shell. With this arrangement the requisite downward reaction on the shell nose is developed on striking water, and a perfect air point is maintained in front of the cup during flight, this air point being more effective than the usual steel point in securing long range.

The slope of the inner walls of the cups, that is, the angle which they make with the axis of the projectile, is another very important consideration. The size of this angle profoundly influences the magnitude of the downward thrust on the shell nose when the projectile strikes water. I have found that for practical purposes this angle should not exceed about 45° and should be much smaller as a rule.

It has been proposed heretofore to provide projectiles with cupped noses to cause them to bite into armor plate upon impact therewith. But such projectiles have always been of the armor-piercing type and the proposed constructions have always been designed solely with this end in view. The proposed cups have always been shallow with obtuse cutting edges so that they would not break upon impact with armor plate but would bite into the same. Moreover said cups have been located close to the ogival point or else at the base. The present invention is not concerned with constructions of this type and the ends sought are wholly different. Moreover, the present invention relates more particularly to projectiles designed not to pierce armor plate but to explode upon the impact therewith and against the outside thereof. For this reason, the cutting edge of this cup is preferably made relatively thin and soft so that it will crush up on striking even thin armor and permit a blow to be delivered on the fuse head contained within said cup. The strength of the cup edges is sufficient, however, to withstand blows incident to ordinary handling.

Another important advantage of the present shell is that for a shell of given dimensions a materially greater interior space is available for the high explosive with which the shell is to be charged. This results from the fact that the virtual length of the present shell is greater than its actual length, owing to the formation of the air point before mentioned when the shell is in flight. This air point takes the place of the steel ogival point in shells as heretofore constructed. It is impracticable to pack ex-

plosive into these steel points and they are usually made solid to enhance their piercing power. Consequently my improved shell in which the actual ogival is truncated 5 has materially greater storage capacity for explosive than does an ordinary shell of the same length. In a 12-inch shell of standard length, this increase in charge capacity amounts in actual practice to as much 10 as 25%.

Another important advantage which results directly from the increased capacity just referred to is that the center of gravity of the explosive charge is thereby brought 15 somewhat nearer the point of the projectile. This is especially important in connection with non-armor-piercing projectiles of the type herein more particularly contemplated, since the charge, which explodes 20 by shock of impact against heavy armor plate, but not by shock of impact against water or thin armor plate, is just that much nearer the surface of the target when the 25 explosion occurs, assuming impact to be at the shell point, and the effect of the explosion on the target is thus heightened to that extent.

Obviously the broad principles of the invention may be embodied in constructions 30 differing in specific details but all coming within the scope of the appended claims. By way of example I have illustrated one form of projectile which the invention contemplates and which has proved successful 35 in actual service.

In these drawings: Figure 1 is a longitudinal section of a complete projectile; Fig. 2 is an end view of Fig. 1, looking from the right; Fig. 3 is a transverse section on the 40 line 3-3 of Fig. 1; Fig. 4 diagrammatically illustrates the position of the shell at various points in its trajectory; and Fig. 5 is a detail partly broken away and in section illustrating the use of a modified form of 45 firing device.

Referring to the drawings, 10 represents the hollow cylindrical body of the shell closed at one end by a heavy base 11, and provided with the usual band 12 for engaging 50 the gun rifling. Toward the opposite end, the shell tapers gradually from a point located approximately at 13 to form the truncated ogival which terminates abruptly at 14. This end of the shell is closed by a 55 cupped nose piece 15, which may be integral with the shell body or which may be a separate member, secured thereto, as here shown, and whose construction will be more particularly described hereinafter. The 60 cupped end thus formed is best located at a point where the ogival diameter is in the neighborhood of one-half the shell diameter. It is to be understood that this location of the cupped nose is capable of being varied 65 within reasonable limits, however. In any

case the cupped nose should be at a substantial distance from both the base and the virtual point of the ogival.

As shown, the base of the charge chamber inclosed by the shell walls is gently coned 70 as at 17, but the angle α included between the conical walls and a plane perpendicular to the shell axis should not exceed 45° in order to substantially eliminate all wedging effect due to pressure of the charge against 75 these conical walls upon setback of the projectile in firing. The lateral walls of the shell gradually decrease in thickness from near the base of the projectile toward a point approximately midway in the length 80 of the projectile, the thickness of the walls being constant from this point to the nose. This decrease in thickness occurs in distinct steps as indicated at 18, 19, and 20, instead of in a curve, the inner walls of the corresponding sections 21, 22, and 23 being truly 85 cylindrical and parallel to the shell axis. By thus shouldering the inner surface of the charge chamber, the thickness of the shell walls may be suitably reduced and the 90 maximum capacity of the charge chamber attained, while at the same time the dangers resulting from the wedging action occasioned by the usual curvature of the chamber walls are entirely avoided. The shoulders 95 18, 19, and 20 also receive a portion of the setback pressure and thus relieve the extreme end of the charge chamber from the total pressure due to the setback of the charge thereagainst; and in order to increase 100 this checking effect, annular ribs or shelves 24 are optionally provided either at the shoulders as here shown, or at other locations along the walls of the charge chamber. The forward faces 25 of these ribs or 105 shelves should be arranged at right angles to the chamber walls, while the rear faces 26 may be sloped as indicated. It will be noted that each succeeding rib of the series, looking toward the rear, as in Fig. 4, projects 110 an increased distance toward the shell axis. Besides serving to check and to distribute the total setback pressure of the charge, these annular ribs also provide gas pockets adjacent their rear faces in which 115 may gather gases which may have resulted from decomposition of the explosive charge where the shell has been filled for a comparatively long period before use. Upon setback of the shell in firing, such gases are 120 liable to be pocketed or trapped in different portions of the firmly packed charge, and the pressure may be sufficient to heat them to such a temperature that they ignite 125 and cause premature explosion of the shell in the gun. In the present arrangement the annular ribs provide a means of separating the charge more or less roughly into sections, and as these sections are compressed by setback, those portions immediately to 130

the rear of each annular rib are more or less free from pressure and thus afford localities into which the gases in question may pass and collect from other portions of the charge in which the pressure has been largely increased by setback. Longitudinal ribs 26^a may also be provided to prevent relative rotational movement between the charge and the shell body. While distinctly advantageous, they are not absolutely essential, and may be dispensed with.

Referring now more particularly to the construction of the nose piece 15, it will be seen that this member is secured in the open end of the shell, in this instance by screw threads 27, the connection being such that upon impact of the end of the shell against thick armor the threads will be stripped and the nose piece or plug will be driven inwardly to compress the explosive in the shell, and thereby assist the fuse in producing an explosion. The outer face of the nose piece or plug is cupped as at 28. The plug is also flanged as at 29, the outer surface of this flange forming a continuation of the ogival surface 16. The inner walls of the cup 28 extend forwardly to the cup edge at an acute angle to the axis of the shell, the angle in this instance being very considerably less than 45°. The edge 30 of the cup is therefore rather sharp.

Provision is made for suitably mounting a fuse device of some kind in the cupped plug 15. In the present instance the plug is formed with a central threaded opening 31, from which may extend rearwardly a tube or hollow casing 32 closed at its rear end and adapted to receive the fuse device 33 which screws into the threaded opening 31. Although here shown integral with the plug, the casing or tube may be separately formed and suitably secured to the plug. By means of the arrangement described, the fuse device may be inserted in the cupped end of the shell or withdrawn therefrom without interfering in any way with the explosive charge. This charge is to be understood as filling the entire space within the shell and to be packed tightly around the casing 32. In filling the shell, a former or core of substantially the same size as casing 32 is inserted into the shell, and explosive is firmly tamped or cast in place around it, the core being then withdrawn and the closing plug 15 being then screwed into place so that the casing 32 occupies the space previously occupied by the core.

The firing or fuse device for detonating the shell charge is most advantageously of the type described in my copending application aforesaid, being provided with a delay action train which is set in operation, as by a percussion cap and pin when the shell strikes water. By using a fuse device of this type in combination with a shell hav-

ing a cupped nose, as herein described, the shell upon striking water will dive to a certain depth during the delay afforded by the delay train, and will then explode, thus acting like a mine. The fuse device is also best provided with quick action firing mechanism, of which the pin or plunger 34, which may be hermetically covered by thin metal 34^a, constitutes a part. Upon impact of suitable intensity, that is, upon impact with a solid target such as armor plate, this pin is driven inwardly and operates in conjunction with other parts to produce practically instantaneous explosion of the shell. This pin or plunger is normally held out of operative position by means which are located within the fuse device and which it is unnecessary to describe here in detail. In order to still further protect the pin from accidentally receiving a blow, the fuse device is so located in the cupped plug 15 that the outer end of the fuse pin is well within the plane of the cup edges 30. These edges therefore protect the pin against accidental impact such as might result from the shell falling down an ammunition hoist or being otherwise dropped on its end while being handled.

In Fig. 5 is shown a modified type of fuse device in which the impact firing pin 35 is normally held inoperative by a split collar or nut 36, each half of which is provided with a spur 37 or the like adapted to engage a complementary recess in the firing pin. The sections of the divided collar are held in the position shown by tapered pins 38 which are normally thrust outwardly by springs 39 in recesses 40 to engage correspondingly tapered grooves on the outer faces of the collar sections. These sections are therefore wedged and locked together, holding the firing pin from being accidentally driven in by any blow to which it may be subjected in ordinary handling. When the shell is fired, the setback drives the pins rearwardly into their recesses against the pressure of said springs and unlocks the collar sections. These latter are then thrown outwardly by the centrifugal force due to the shell spin, leaving the firing pin free to be driven in upon impact of sufficient intensity.

The use of a cupped nose in connection with the type of firing pin just described has special advantages in that the cup retains the collar sections until after the shell has left the gun, thus preventing the shell being jammed in the gun by one or both collar sections becoming wedged between the ogival and the rifling of the gun.

What I claim is:

1. A projectile comprising the combination, with a hollow shell of generally cylindrical form inclosing a single continuous and substantially unobstructed charge cham-

- ber, the inner walls of said shell being stepped or shouldered to provide pressure-distributing setback abutments, of a charge substantially filling said charge chamber and bearing rearwardly against such steps or shoulders.
2. A projectile comprising a hollow shell of generally cylindrical form inclosing a single continuous and substantially unobstructed charge chamber, the inner walls of said shell being provided with series of annular ribs projecting toward the shell axis, each succeeding rib from the front member of the series toward the rear projecting an increased distance toward the shell axis.
3. A projectile comprising a hollow cylindrical shell, the inner walls of which are provided with a series of annular ribs projecting toward the shell axis, each of said ribs having a forward face substantially at right angles to said axis and a rear face inclined rearwardly from its inner edge to the shell wall.
4. A projectile adapted to dive on striking water and comprising a cylindrical body and a truncated ogival terminating in a cupped nose, said cupped nose having a relatively thin sharp front edge and being located intermediate the ogival base and the virtual ogival point and at a substantial distance from both.
5. A projectile adapted to dive on striking water and comprising a cylindrical body and a truncated ogival terminating in a cupped nose, said cupped nose being located approximately where the diameter of the ogival is about one-half the diameter of the projectile, and the inner walls of said cup extending forwardly to the edge at an angle of materially less than 45° with the axis of the projectile.
6. A projectile adapted to dive on striking water and comprising a cylindrical body and a truncated ogival terminating in a cupped nose or point, the inner walls of the cup adjacent the margin thereof being at an angle of not more than about 45° to the projectile axis.
7. In a projectile, the combination, with a shell adapted to contain a charge explosive by shock of impact of the projectile in flight against heavy metal but not explosive by shock of impact against water, said shell having a cupped point adapted to cause the shell to dive upon striking water, of fuse mechanism for exploding said charge comprising a delay action train arranged to be set in operation by impact of the shell with water.
8. In a projectile, the combination, with a shell containing a charge explosive by shock of impact of the projectile in flight against heavy metal but not explosive by shock of impact against water, said shell having a point so formed as to cause the shell to dive upon striking water, of a detonating device arranged to be set in operation by impact of the shell with water and to detonate said charge a predetermined period of time after such impact.
- In testimony whereof I have signed this specification in the presence of two subscribing witnesses.
